UNITED STATES PATENT OFFICE

JURJEN S. HIGH, OF WILKINSBURG, PENNSYLVANIA, ASSIGNOR TO WESTINGHOUSE ELECTRIC & MANUFACTURING COMPANY, A CORPORATION OF PENNSYLVANIA

REPRODUCING DEVICE

Application filed July 30, 1927. Serial No. 209,447.

My invention relates to reproducing devices, and although it finds its largest field of usefulness in connection with reproducing devices of the type known as "loud speakers", it is also applicable to many other electrodynamic devices designed and intended to translate electrical current, or electrical potential variations into mechanical movements or into air-pressure fluctuations and vice versa.

Substantially all telephone receivers and loud speakers in common use up to the present time may be divided into three general classes, according to the manner in which the 15 electrical variations are translated into mechanical movements, i. e., those in which a magnetic diaphragm is directly actuated by an electromagnet, those in which an armature connected to a diaphragm is caused to 20 vibrate by magnetic means and those in which a coil moving in a magnetic field is connected to a diaphragm to transmit motion thereto.

Sound reproducers of the last above-mentioned type are greatly handicapped by the necessity of providing flexible leads between the moving coil and the source of electrical variations, which eventually break and thus cause trouble.

30 In his Patent No. 1,167,366, Fessenden points out that a single short-circuited turn may be substituted for the multi-turn coils previously utilized, thus eliminating the necessity for moving leads. Although theoretically operable, the Fessenden device is extremely inefficient and fails entirely to meet the exacting demands imposed upon a loud speaker for the reproduction of high-quality music, such as is at present being recorded 35 on phonograph records and being broadcast ed by various radio transmitting stations.

One object of my invention, accordingly, is to provide a reproducing device analogous, in some respects, to the device shown in 45 the aforementioned Fessenden patent, in which the efficiency, i. e., the relation of sound-energy output to electrical energy input, is greatly improved.

Another object of my invention is to provide a sound reproducing device of the type

referred to wherein neither high nor low frequencies are accentuated in the sound output.

The above objects, and other incidental and relative thereto, I attain by the utilization of an improved magnetic circuit, and by providing a moving, short-circuited actuating element of a peculiar type to cooperate therewith. Specifically, my improved magnetic circuit includes a plurality of air-gaps, as 55 distinguished from the single air-gap of prior constructions. In addition, I have greatly reduced the losses caused by eddy-currents in the magnetic field elements by so laminating the said elements that an extremely high impedance is introduced into the path normally followed by such currents.

Among the novel features of my invention are those particularly set forth in the appended claims. The invention itself, however, both as to its organization and its method of operation, together with further objects and advantages thereof, will best be understood from a consideration of the following description of certain specific embodiments, taken in connection with the accompanying drawings, in which:

Figure 1 is a sectional view of one embodiment of my invention in which a permanent magnet is utilized.

Fig. 2 is a sectional view taken along a line corresponding to the line II—II of Fig. 1, as seen from below.

Fig. 3 is a view, partly in section and partly in elevation, of a further modification of my invention.

Fig. 4 is a sectional view taken along a line corresponding to the line IV—IV of Fig. 3, as seen from below.

Fig. 5 is a view, partly in elevation and partly in section, of a still further modification of my invention wherein an electromagnet is utilized.

Fig. 6 is a view, in elevation, of one of the individual laminations employed in building up the central pole piece shown in Fig. 5.

Fig. 7 is a view of one of the laminations utilized in the construction of the annular pole piece illustrated in Fig. 5, and

Fig. 8 is a sectional view, taken along a line 100

corresponding to the line VIII—VIII of Fig. 5, as seen from below, illustrating the manner in which the pole pieces are laminated.

Referring specifically to Fig. 1, a modification of my invention suitable for use in connection with two sound-radiating horns comprises a base plate 1 of magnetic material having an opening 2 therethrough adapted to receive the small end of a horn. The base 10 plate is further provided with two concentric ring-shaped extensions 3 and 4, the inner surface of the latter extension being coaxial with the opening 2. A ring-shaped member 5 of magnetic material is mounted on the extension 4 and is provided with a channel 6 in which is positioned a coil of wire 7 adapted to carry fluctuating currents which are to be translated into air-pressure variations.

The outer ring-shaped extension 3 of the 20 base plate carries a second circular element 8 of magnetic material upon which is mounted, by means of a plurality of screws 10 or analogous devices, a base plate 11 of non-magnetic material, provided with an extension 12 into 25 which the small end of a horn may be inserted.

A light cup 13 of any suitable non-magnetic material is supported with its edge or skirt 14, lying in the magnetic field existing between the circular element 8 and the interior circular element 5 which carries the coil 7. The cup is preferably spun from a sheet of aluminium, not over 4 mils thick, and is suspended from an annular mounting ring 15 made of soft rubber or analogous material. 35 The outer edges of the suspension ring are clamped between the circular element 8 and the base plate 11.

The circular element 5 carrying the coil 7, is magnetized to have one polarity, while the 40 ring 8, carried by the magnetic base plate 1, is given the opposite polarity. If these elements are made of a material such as cobalt steel, a strong magnetic field will exist across the gap between the extension 8 and the 45 flanges of the central circular pole piece 5. The gap may be made extremely small, and, in one actual embodiment of my invention, it was approximately 24 mils.

When an alternating current is caused to 50 flow in the coil 7, this coil acts as the primary of a step-down transformer, the secondary of which is the skirt of the cup 13. The potentials set up, therefore, in the skirt are in such direction as to cause eddy-currents to flow 55 around it. These eddy-currents, reacting with the fixed magnetic field in which the cup lies, cause the cup to move in the air gap with an amplitude and frequency corresponding to the amplitude and frequency of the exciting 60 current in the coil.

The bottom of the cup is essentially a piston-diaphragm and its motion causes a compressional wave to emanate from the opening in the magnetic base plate 1 in phase with a rarefaction wave emanating from the

opening in the non-magnetic base plate 11. By suitably choosing the length of the horns mounted on the base plates, and by properly positioning their mouth openings relative to each other, the sounds issuing therefrom may be combined without interference phenomena being apparent.

I have established, by research and experiment, that, by reason of the skin-effect phenomenon, which is more apparent at high frequency, the eddy-currents induced in the cup 13 will tend to crowd toward the free edge and toward that portion thereof which merges into the diaphragm portion. The crowding of the current, at high frequencies, away from the mid-section of the skirt into those regions thereof subjected to the densest magnetic field markedly increases the efficiency of the device over similar devices known to the prior art. Inasmuch, however, as the uneven distribution of the eddy currents is the more pronounced the higher the frequencies involved, the device tends to some extent to accentuate the higher frequencies at the expense of the lower, notwithstanding the fact that the Foucault, or eddy-current losses in the pole pieces increase as the frequency is raised.

A fair balance between the response to high and low frequencies may be obtained by properly laminating the pole pieces in the manner clearly shown in Fig. 2, but, in spite of this precaution, the device, as shown in Fig. 1, is very apt to be preferentially responsive to high frequencies.

In order, therefore, to provide a device which is inherently capable of giving an even response over a wide range of excitation frequencies, I have added an additional air gap to the magnetic circuit illustrated in Fig. 1, and have so positioned this additional air gap that the permanent flux thereacross cooperates with eddy-currents induced in the cup at low frequencies. A further modification of my invention is illustrated in Fig. 3.

Referring specifically to Fig. 3, a central pole piece 20 of cold-rolled steel has affixed to one end thereof a core 21 of nickel-iron alloy by means of a bolt 22 which passes through the bottom of an opening 23 in the core and is threaded into an opening 24 in the pole piece. The core is preferably provided with a plurality of radial saw-cuts, as shown in Fig. 4.

A circular collar 25 of non-magnetic material, such as brass or bronze, encircles the core 21 and is retained thereon by a set screw 26. The collar 25 carries an annular pole-piece assembly which comprises a plurality of discs 27, 28 and 30, preferably made of a nickel-iron alloy, and having aligned central openings through which the core 21 extends. Those portions of the discs immediately adjacent to the central core are provided with radial saw-cuts, as shown in Fig. 4.

The disc 27 has a portion 31 thereof offset from the disc 28, and the disc 30 also has a central offset portion 32. The annular space between the offset portion of the disc 27 and the central disc 28 accommodates a coil 33, while a similar annular coil 34 is positioned in the space between the offset portion of the disc 30 and the central disc. These coils are electrically connected in series-aiding relation and are designed to carry the currents representing sound frequencies. The assembly of discs may be held together by a plurality of bolts 35, as shown, and the entire assembly is held in position on the collar 25 by a plurality of similar bolts 36.

The air gap between the core 21 and the inner edges of the discs 27, 28 and 30 is made extremely small and may be of the order of 5 mils.

20 The magnetic circuit is completed through two L-shaped permanent magnets 37 and 38, made preferably of cobalt steel, and rectangular in cross section. The short ends 40 and 41 of the magnets are held in contact with one end of the central pole piece 20 by means of a plurality of collars 42 and 43, which are tensioned toward each other by a plurality of bolts 44. The long ends 45 and 46 of the permanent magnets abut the inner disc 27 of the pole-piece assembly and are maintained in firm contact therewith by the action of a plurality of set screws 47 carried by a non-magnetic bridge-member 48 which is affixed to the end of the pole piece by means 35 of a plurality of screws 50. The collars and the tie rods are of non-magnetic material.

40 The discs comprising the annular pole-piece assembly are preferably made of a nickel-iron alloy and are laminated as illustrated in Fig. 4, and a diaphragm housing device 51 of non-magnetic material, provided with an extension 52 upon which a horn may be mounted, is affixed, by a plurality of bolts 53, to the pole-piece assembly. The diaphragm housing comprises a circular element 54 which is held directly in contact with the pole-piece assembly and a second circular element 55 clamped thereto by a plurality of screws 56. A diaphragm is held between the two elements, pressure thereon being exerted by the screws 56.

45 The diaphragm 57 carries a cylindrical element 58, preferably spun from aluminum having a thickness not appreciably greater than 4 mils. The element 58 encircles the central core and lies in the air gaps determined by the inner edges of the pole-piece assembly discs. The cylindrical element is attached to the diaphragm by a plurality of integral extensions 60, which are so proportioned as to interpose a definite amount of compliance between the diaphragm and the said cylindrical member.

50 In order that the cylindrical member may be accurately centered in the air gap, the holes

in the diaphragm housing element 54, through which the bolts 53 extend, are purposely made somewhat larger in diameter than the said bolts, thus permitting the diaphragm housing to be shifted laterally with respect to the pole-piece assembly, before the bolts 53 are tightened. The centering operation may be easily accomplished while the device is being first assembled, or while it is in operation later, by merely loosening the screws 53 and moving the diaphragm housing until any audible rattles or scraping sounds disappear. In the initial assembly, it is preferable to energize the device by a relatively low-frequency current of high amplitude, in order that any defects in the centering may be detected.

55 The magnetic circuit for the flux set up by the current variations in the coil 33-34 may be traced from the inner edge of the disc 27, through the adjacent portion of the central core 21 and back through the inner edge of the disc 30. The inner edge of the central disc is not subjected to flux variations caused by the current in the coil, and consequently, the flux between it and the central pole-piece is constant in amplitude.

60 Circulating eddy-currents are caused to flow in the cylindrical element by reason of the fact that it constitutes a short-circuited secondary of a step-down transformer of which the coil 33-34 is the primary. As previously explained, the eddy-currents, when at high frequencies, tend to be crowded towards the ends of the cylindrical element, and consequently, react with the flux in the air gaps between the outer pole-piece discs and the central core. The eddy-currents, at low frequencies, which are not so crowded toward the ends of the cylindrical element, react with the flux across the gap between the central disc 28 and the core and are, consequently, equally as effective as the high-frequency currents in causing motion of the cylindrical elements.

65 The complete embedding of the actuating coil in the pole-piece, as distinguished from the manner in which this coil is mounted according to the aforementioned patent to Fessenden, results in a decided increase in the efficiency of the device. Such construction also permits a very decided reduction in the width of the air gap, which not only tends to reduce the leakage flux, but also permits the permanent flux to more efficiently react with the eddy-currents induced in the cylindrical element.

70 By providing a plurality of spaces in which the primary or actuating coil may be wound, the reluctance of the magnetic circuit which carries the flux induced by the varying current in this coil is greatly reduced, and, at the same time, the reluctance in the fixed magnetic circuit is also diminished. In addition, the provision of one set

of air gaps to cooperate with those portions of the cylindrical element which carry the major portion of the eddy-currents at high frequency and another air gap to cooperate with that portion of the cylindrical element which carries the currents at low frequencies results in a device which neither accentuates the high nor the low frequencies.

I have also found it feasible to further increase the sub-division of the air gap and the actuating coil, but the improved results obtained do not seem to be commensurate with the additional expense involved.

Instead of providing the solid central core and the circular disc-shaped pole pieces with radial saw-cuts to minimize losses caused by eddy-currents, it is possible to construct the said pole pieces from a plurality of laminations in much the same manner as the armature of an electric motor is constructed. As an example of this type of construction, reference should be made to Figs. 5 and 8, which illustrate only the magnetic element thereof, the diaphragm housing, the dia-

25 phragm and the cylindrical diaphragm-actuating element being omitted therefrom.

Referring specifically to Fig. 5, a central pole-piece 65 of magnetizable material carrying a magnetizing winding 66, is mounted in the interior of a cup-shaped element 67, also made of magnetizable material, and is held in position by means of a bolt 68. The end of the pole-piece opposite the end that is in contact with the cup-shaped element is provided with an axial opening in which are radially positioned a plurality of laminations 70 shaped as shown in Fig. 6, which laminations are separated one from another, by insulating material and are held in position by a metallic wedge 71.

A non-magnetic spacer disc 72 is mounted on the pole-piece immediately adjacent to the portion thereof which carries the laminations 70, and interposed between this disc and the cup 67 is a ring 73 of magnetic material provided with a channel 74 concentric with the opening in the central pole-piece. A plurality of laminations 75, shaped as shown in Fig. 7 and made of magnetizable material, are arranged radially of the central pole piece, the inner ends thereof being spaced a slight distance therefrom, and a portion of the outer ends lying in the aforementioned channel 74. The laminations 75 are clamped firmly between the ring 73 and a similar ring 76, a plurality of tie-bolts 77 serving to hold the assembly of rings and laminations together.

Each of the laminations 75 has a plurality of extensions 78 which, when the said laminations are arranged radially, as shown in Fig. 8, constitute the boundaries of circular grooves adapted to receive and hold the portions of a winding 80 through which the

currents representing sound-frequencies may be passed.

The exact contours of the laminations 70 and 78 are not material, it being entirely feasible to so modify them that they may be stamped or punched from flat sheets with less waste than the forms shown by way of illustration.

My invention is mainly advantageous in that it enables the provision of a loud-speaker of the eddy-current type that has an even response to a wide range of actuating frequencies. Further, by laminating the pole pieces and by imbedding the speech-winding therein I have greatly reduced the attendant losses, and have produced a loud-speaker that has a high degree of efficiency.

Although I have illustrated and described only a few specific embodiments of my invention, numerous obvious modifications thereof will be suggested to those skilled in the art. My invention, therefore, is not to be limited except in so far as is necessitated by the prior art, and by the spirit of the appended claims.

I claim as my invention:

1. In reproducing apparatus, a magnetic circuit comprising a pole in the form of an inner core, a second pole having more than two annular portions surrounding the inner pole and forming therewith more than two air-gaps, and a cylindrical movable element fitting over said inner pole and lying partially in said air-gaps.

2. In reproducing apparatus, a magnetic circuit comprising a pole in the form of an inner core, a second pole having more than two annular portions surrounding the inner pole and forming therewith a plurality of annular air-gaps, a cylindrical movable element fitting over said inner pole and lying partially in said air-gaps, and a continuous coil of wire comprising sections completely imbedded in the annular spaces between said annular portions.

3. In reproducing apparatus, a magnetic circuit comprising a pole in the form of an inner core, a second pole having more than two annular portions surrounding the inner pole and forming therewith a plurality of annular air-gaps, a cylindrical diaphragm-actuating element fitting over said central pole and lying partially in said air-gaps, resilient supporting means for said element, and actuating coils lying in the annular spaces between said annular portions.

4. In reproducing apparatus, a magnetic circuit comprising a pole in the form of an inner cylindrical core, and a second pole having annular portions surrounding and projecting toward the inner pole and forming therewith a plurality of annular air gaps, the said inner pole being radially laminated.

5. In reproducing apparatus, a magnetic circuit comprising a pole in the form of an

inner cylindrical core, and a second pole having annular portions surrounding and projecting toward the inner pole and forming therewith a plurality of air-gaps, the said annular portions being radially laminated.

6. In reproducing apparatus, a magnetic circuit comprising a pole in the form of an inner cylindrical core, and a second pole having annular portions surrounding and projecting toward the inner pole and forming therewith a plurality of air-gaps, both said inner pole and said annular portions being radially laminated, whereby the circulation of eddy-currents therein is impeded.

10 7. In reproducing apparatus, a magnetic circuit comprising a pole in the form of an inner core, a second pole having annular portions surrounding and projecting toward the inner pole and forming therewith a plurality of air-gaps, both of said poles being radially laminated, and a plurality of annular coils of wire imbedded in the annular spaces between said annular portions.

15 8. In apparatus for sound reproduction, a cylindrical metallic diaphragm-actuating element, a diaphragm, and a plurality of independent connecting devices between said diaphragm and said element, said devices each having an axially rigid portion and a portion flexible in the direction of movement of said diaphragm.

20 9. In apparatus for sound reproduction, a cylindrical metallic diaphragm-actuating element, a diaphragm, and a plurality of devices connecting said element and said diaphragm, said devices extending substantially axially of said element and each having an axially rigid portion and a flexible portion.

25 10. In apparatus for sound reproduction, a cylindrical metallic diaphragm-actuating element, a diaphragm, and a plurality of devices connecting said element and said diaphragm, said devices being integral with said element and extending axially thereof, each of said devices having an axially rigid portion and a flexible portion.

30 11. In apparatus for sound reproduction, a cylindrical metallic diaphragm-actuating element, a diaphragm, and a plurality of independent devices connecting said element and said diaphragm, said devices each comprising a portion extending axially of said element and a portion extending perpendicularly to the axis of said element, whereby the connection between said element and said diaphragm may be given a predetermined amount of resiliency.

35 In testimony whereof, I have hereunto subscribed my name this 23rd day of July, 1927.

JURJEN S. HIGH.
